UNITED STATES PATENT OFFICE

HENRY E. SCHNEIDER, OF ERIE, PENNSYLVANIA, ASSIGNOR TO HAYS MANUFACTURING COMPANY, A CORPORATION OF PENNSYLVANIA

TUBE BENDING MACHINE

Application filed August 4, 1930. Serial No. 472,826.

This invention relates to a pipe and tube bending machine of the portable type, but constructed to permit the same to be clamped in position and used as a stationary type of bending machine. The improved machine is of simplified construction adapted for bending copper, brass, iron or steel pipe or tubing and arranged for the removable reception of pipe handles for quick bending on a job and furthermore arranged for the removable reception of a reduction lever device for making pipe bends in close quarters by means of a clip-carrying forming block or sheave having pivotally mounted thereon, by means of a removable king-pin, a forming slide, whereby a pipe or tube engaged between the forming block and the forming slide and clamped by means of the holding clips is bent with the aid of a pawl and ratchet mechanism without crushing or stretching of portions of the pipe, and acting to iron out any wrinkles or irregularities that might be in the pipe or tube which is being bent.

It is an object of this invention to provide an improved, simplified type of pipe and tube bending machine operable by means of removable long handles or by means of pivotally connected, fulcrumed reduction levers where the amount of space for operation of the machine is limited.

It is also an object of this invention to provide an improved pipe or tube bending machine adapted for use either as a portable or stationary device and arranged to be placed in position on a pipe or tube at any point in the length thereof to make a bend in the pipe without causing dents or kinks and without disturbing the fixed end of a tube or pipe.

It is a further object of this invention to provide an improved type of pipe and tube bending machine wherein a ratchet forming block has associated therewith lever-operated pipe bending mechanisms for making smooth finished, rounded bends without dents or kinks, even in dark or poorly lighted places, by simply counting the number of notches with which the pawl is brought into coacting relation by an improved arrangement whereby the movement through the

ratchet notches is arranged to produce a bend of a predetermined number of degrees.

It is furthermore an object of this invention to provide an improved type of pipe and tube bending machine wherein an improved ratchet-carrying forming block is equipped with spring-controlled pipe-holding clips constructed to prevent opening of the clips under pressure of bending of a tube when acted on by lever-operated, pivotally mounted blocks, one of which carries a pawl for coaction with the ratchet forming block, while the other is supported by means of a removable king-pin for sliding coaction with a pipe or tube to smoothly bend the same without compressing or stretching of the pipe or tube and acting as a means whereby any wrinkles may be ironed out before a bending operation takes place.

Still another object of the invention is to provide an improved type of portable and stationary tube bending machine wherein a clip-carrying forming block has removably engaged thereon, by means of a king-pin, a forming slide for coaction with a pawl-carrying block, said forming slide arranged so that all bending pressures are exerted on the king-pin from opposite directions to equalize all the strains on the forming block and the forming slide.

It is also an object of this invention to provide an improved, simplified type of pipe and tube bending machine wherein a forming sheave is provided with a removable forming slide, the length of which is in direct proportion to the radius of the forming sheave, whereby the forming slide is adapted to act on a tube before bending the same to iron out any wrinkles that might be in the tube and then bending the tube without distorting the cross-section of the tube and without stretching the same.

It is an important object of this invention to provide an improved, simplified and inexpensive type of pipe and tube bending machine constructed to be used either as a portable or stationary machine, and adapted to smoothly bend pipes or tubes from a straight position to substantially any degree angle up to 180°, said degree of bending being

determinable by the relative movement of a control pawl with respect to ratchet teeth provided on the side of the forming block of the machine and spaced at predetermined degrees to facilitate the determination of the degree of bending of the pipe or tube in the machine.

Other and further important objects of this invention will be apparent from the disclosures in the specification and the accompanying drawings.

The invention (in a preferred form) is illustrated in the drawings and hereinafter more fully described.

15 On the drawings:

Figure 1 is a side elevation of an improved tube bending machine embodying the principles of this invention, showing a portion of a tube in position ready to be bent and 20 illustrating the operation of the forming slide and reduction levers in dotted lines, in addition to illustrating in dotted lines the positioning of removable handles for operation of the machine when the reduction levers 25 are omitted.

Figure 2 is an enlarged fragmentary detailed section of the pawl and ratchet mechanism taken on line II—II of Figure 1.

Figure 3 is an enlarged end elevation of 30 the bending machine when the same is inverted and mounted in clamped position in a support to afford a stationary type of bending machine, illustrating the open position of the holding clips in dotted lines and showing the clamping position of the clips in full lines.

Figure 4 is a sectional view of the device taken on line IV—IV of Figure 1 with parts 40 shown in elevation and also illustrating a removable stop member clamped on the rim of the forming sheave.

Figure 5 is a fragmentary view taken on line V—V of Figure 1 with the tube omitted.

As shown on the drawings:

45 The improved machine is a portable hand type bender constructed to permit the same to be also used as a stationary bender and adapted for smoothly bending, without denting, crushing, stretching or distorting of hollow passaged articles, such as copper, brass, iron or steel pipe or tubing, or solid articles, such as rods, bars and the like.

The machine comprises a forming block in the form of a wheel, pulley or sheave embracing a hub 1, an integral disc or spoke section 2 and a rim or felloe 3 constructed with a peripheral pipe or tube-receiving groove 4. The forming block has a segment thereof cut away to provide a recess or pocket bounded 55 by walls or surfaces 5 and 6 which are disposed at substantially right angles to one another.

60 Integrally formed or rigidly mounted on one side of the rim or felloe 3 is an arcuate ratchet comprising a plurality of ratchet

teeth 7 separated by ratchet notches 8. The arcuate ratchet extends for substantially 180° around one side of the forming block rim 3, as clearly illustrated in Figure 1, and has the ends thereof terminating a short distance from the end walls 5 and 6, leaving plain arcuate side surfaces in the rim between the ends of the ratchet and the ends of the felloe or rim of the forming block. While the ratchet is described as extending for substantially 180° around one side of the forming block, it will, of course, be understood that the ratchet may, if desired, be made of any desired length, depending upon requirements.

For the purpose of rigidly clamping or holding one end of a pipe or tube properly seated within the groove 4 of the forming block, a pair of clip arms 9 are pivotally mounted at their inner ends upon a supporting bolt 10, the threaded end of which is secured in a threaded opening provided in the wall or surface 5 of the notched out portion of the forming block. The screw bolt 10 is positioned substantially parallel to the surface 6. Engaged around the shank of the screw bolt 10 is a coiled control spring 11. The control spring 11 is positioned between the head of the bolt 10 and the outermost clip arm 9, as clearly illustrated in Figure 1. The spring 11 serves to resiliently hold the ends of the clip arms about the pipe or tube in resilient frictional contact with each other. Each of the clip arms 9 has the outer end thereof curved to afford a holding head 12 with a rounded inner surface or pocket at 13, so that, when the pair of clip arms are engaged around a tube or pipe 14, the heads of said arms have bearing contact with the outer peripheral surface of the pipe or tube more than half way around, as clearly illustrated in Figure 3. This contacting of the heads of the clip arms more than half way around the pipe or tube which is to be bent serves to prevent crushing or sectional distortion of the article which is being bent. The clip heads or hooks 12 each have integrally formed on the outer end thereof a finger or wing 15 which projects beyond the hook or head 12 and is slightly bent out of the plane of the head or hook 12, as clearly illustrated in Figure 5. The inner side of each of the fingers or wings 15 where it integrally joins the head or hook 12 is provided with an angled notch or recess 16 which forms a stop tooth over which the finger or wing of the adjacent clip arm is adapted to snap due to the action of the control spring 11 to prevent opening of the clips under pressure of bending when the machine is in operation. When the clip arms are swung inwardly toward each other to engage over a pipe or tube, the inclined fingers or wings 15 frictionally pass each other, and, as soon as the toothed or notched portions 16 thereof are passed,

the action of the control spring 11 serves to snap the heads or hook portions of the clip arms together around the pipe or tube, thereby locking the clips against outward swinging movement away from each other so that there is no danger of the pipe or tube being released during a bending operation. After a bending operation, the clip members may be readily released by merely pressing with the thumb and forefinger in opposite directions on the fingers or wings 15 to release the locking engagement of the heads or hook portions of the clip arms to allow the same to be swung outwardly away from each other and out of engagement with the bent pipe or tube.

Rigidly mounted axially within the hub 1 of the forming block is a cylindrical bushing or bearing sleeve 17 the ends of which project beyond the sides of the hub 1. Pivotally engaged on the projecting ends of the bushing or bearing sleeve 17 are the apertured inner ends of the arms 18 of a pawl block of forked or U-shape construction embracing the arms 18 and a head 19 integrally connecting the same. Integrally formed on one side of the pawl block head 19 are a pair of spaced flanges or ribs 20 affording a space therebetween for receiving a control pawl 21 which is pivotally mounted on a supporting pin 22 engaged through the flanges or ribs 20. One end of the control pawl 21 is positioned for coaction with the teeth and notches 7 and 8 of the ratchet formed on one side of the forming block. For the purpose of insuring proper engagement of the pawl 21 with the ratchet, a control spring 23 is seated in suitable recesses provided in one of the pawl block arms 18 and the outer end of the pawl 21, as clearly illustrated in Figure 2.

Threaded into an opening in one side of the pawl block head 19 adjacent the outermost pawl-supporting flange or rib 20 is the inner threaded end of a screw pin or stud 24 positioned to afford a support for the engagement of one of a pair of pivotally connected reduction levers 25. The reduction levers 25 are adapted for operation of the machine and have two ends thereof pivotally connected together by a pivot pin 26. Each of the reduction levers 25 is provided with an opening at 27 for selective engagement with the levers to be engaged on the fulcrum pin 24. The outer end of the pawl block head 19 is provided with an internally threaded recess or pocket 28 (Fig. 3) for the removable reception of the threaded end of a pipe like handle 29 when the machine is to be operated by means of handles instead of by means of the reduction levers 25. The positioning of the operating handle 29 is illustrated in dotted lines in Figure 1 of the drawings.

Mounted for coaction with the pipe or tube 14 for bending of the same is a forming slide

comprising a block or arm 30 which is formed with a longitudinal rounded groove 31 to seat on the pipe or tube 14 when the slide 30 is positioned ready for bending as illustrated in Figure 1 of the drawings. Integrally formed or rigidly secured to one end of the forming slide block or arm 30 is a pair of legs or supporting arms 32 and 33 parallel to each other and having apertures near the outer ends thereof for the removable reception of the straight shank of a king-pin 34. One end of the king-pin 34 is chamfered or pointed to facilitate mounting of the forming slide on the forming block. The apertured arms or legs 32 and 33, comprising a part of the forming slide 30, are positioned on opposite sides of the arms 18 of the pawl block, with the openings in the arms or legs 32 and 33 registering with the ends of the bearing sleeve or bushing 17, as clearly illustrated in Figure 4. The king-pin 34 is provided with an enlarged head 35 and has a handle or actuating pin 36 projecting diametrically therethrough for insertion and removal purposes.

The king-pin 34, when inserted in position, projects through the aperture in the leg 32 and through the bearing sleeve 17 and has the tapered or pointed end thereof projecting through the opening in the forming slide leg 33 and is seated in a clearance hole of a boss 37 formed on the outer side of the supporting leg or arm 33, as clearly illustrated in Figure 4, to afford an arrangement whereby the king-pin is prevented from being knocked out of engagement with the back arm or leg 33 of the form slide.

The form slide arm or block 30 is provided with an internally threaded opening in one side thereof for the reception of a screw pin or stud 38 which projects outwardly at substantially right angles to the block 30 in a convenient position whereby the aperture 27 in one of the reduction levers 25 may be engaged thereon when the other reduction lever has the aperture thereof engaged over the pin or stud 24, as illustrated in Figure 1. The pivotally connected reduction levers 25 are provided to facilitate operation of the bending machine in close quarters. When it is necessary to perform a quick bending operation on the job, the reduction levers may be omitted and long handles 29 and 39 used instead. As illustrated in Figure 1, the long handle 39 at one end thereof is threaded or otherwise formed to facilitate engagement of the handle in a threaded opening provided in the end of the block or arm 30 of the forming slide.

For the purpose of permitting the machine to be used as a stationary machine instead of one of the portable type, the forming slide block or arm 30 is provided with an integral rib or web 40 which may be inserted in a vice or gripping support 41, as illus-

trated in Figure 3, to rigidly clamp the forming slide in a stationary position.

Referring now to the forming block and the ratchet formed on one side thereof, any degree of angle bend may be produced in a pipe or tube from zero to substantially a complete U bend, even in the dark or in a poorly lighted place, due to the spacing of the ratchet teeth or notches a predetermined number of degrees apart, so that it is simply necessary to count the number of notches that the pawl 21 engages during a bending operation. It will thus be noted that the degree of bending may be readily determined by merely counting the number of notches engaged by the control pawl 21, since the teeth of the ratchet are all spaced predetermined degrees apart. With this arrangement, it is, therefore, unnecessary to read any scale figures or the like which are usually placed on the forming block to facilitate determining the angle of bend of a pipe or tube.

The operation is as follows:

When the machine is to be used for the purpose of bending a pipe or tube or other article, the king-pin 34 is pulled out and the forming slide is removed. The clip arms 9 are swung into open position, as illustrated in dotted lines in Figure 3, and the straight pipe or tube 14 is seated in the groove 4 of the forming block with a portion of the pipe or tube projecting over the notch or recess provided in the forming block. The clip arms 9 are then swung inwardly towards each other and engaged over the tube 14, with the wings or fingers 15 of the clip arms passing each other until the notches 16 of said fingers pass each other, allowing the control spring 11 to snap the heads of the clips together, thereby locking the same around the pipe or tube 14 with the curved edges of said clip members contacting the tube more than half way around the same, thereby affording an arrangement for reducing the tendency of any crushing or deforming of the tube during a bending operation as the clips exert side pressure against the pipe or tube. The forming slide arm or block 30 is now seated on the tube 14, as illustrated in Figure 1, and the king-pin is inserted through the legs 32 and 33 of the forming slide to pivotally hold the same supported in position in coacting relation with the pawl block and with the forming block of the device. The length of the forming slide arm or block 30 is in direct proportion to the radius of the forming block so that, during a bending operation, the forming slide acts to bend the pipe or tube 14 without causing stretching of the same. The long bearing surface which the block 30 has with the pipe or tube also serves as a means to cause ironing out of any wrinkles that might be in a pipe or tube before a bending operation actually takes place. With the pipe or tube engaged in position as described, the

pawl block is pivotally swung around the forming block by depressing the outer end of the pawl 21 and releasing the inner end thereof from engagement with the ratchet. The pawl block is swung around into a close position adjacent the forming slide arm or block 30, similar to the arrangement illustrated in Figure 1, with the pipe extending between the forming slide block 30 and the pawl block. The reduction levers 25 are now engaged on the two pivot pins 24 and 38 so that the outer ends of the reduction levers 25 project away from each other.

To bend a pipe or tube 14, the two reduction levers are forced together, and, since the control pawl 21 has the inner end thereof engaged in one of the notches or against one of the teeth of the ratchet, the pawl block is held against movement with respect to the forming block, so that, when the levers are forced together, the forming slide is swung about the king-pin 34 as an axis from the full line position in Figure 1 toward the dotted line position approaching the pawl block and causing the engaged pipe or tube to be bent evenly through a predetermined number of degrees. After a bending operation, the pawl block is adapted to be moved away from the forming slide in its then position, permitting the spring-controlled pawl to slide into another position of engagement with the ratchet, after which the reduction levers are again pressed together, causing the partially bent pipe or tube to be still further bent through a predetermined number of degrees, depending upon the position of the pawl with respect to the ratchet. The bending operation may thus be repeated until the pipe has been smoothly bent through the required number of degrees.

In case it is desired to bend a plurality of different pipes or tubes through the same degree angle, the rim of the forming block has removably engaged thereon a T-slotted stop member or block 42 which is equipped with a thumb screw 43 whereby the stop block may be secured in a predetermined position of adjustment on the rim of the forming block, as illustrated in Figure 4, to limit the swing of the pawl block and thereby determine the degree of bend of the various pipes bent by the bending machine.

After a pipe bending operation, the reduction levers are removed from engagement with the pins 24 and 38, and the king-pin 34 is pulled out, thereby permitting the forming slide to be removed from engagement with the bent pipe or tube. Pressure with the thumb and forefinger against the wings or fingers 15 of the clip arms causes the clip arms to be resiliently moved or swung apart against the action of the control spring 11 so that the locking engagement of the head ends of the clip arms is broken, thereby permitting the clip arms to be swung outwardly

away from one another to release the bent pipe or tube.

The pawl block 19, carrying the pawl 21, is conveniently moved by the reduction levers 5 engaged therewith after every bending operation of a pipe or tube through a distance of one or two notches of the ratchet. The machine, when using the pivotally connected reduction levers 25 as the operating medium for 10 causing bending of pipes or tubes, is adapted to be used in close quarters. During a bending operation, the bending pressures are exerted on the king-pin 34 and the bushing 17 from opposite directions, thereby equalizing the strains upon the forming block and 15 the forming side.

When a quick bending operation is to be performed and there is plenty of space, the machine is engaged on the pipe or tube to be bent, and, instead of using the pivotally connected reduction levers, the long handles 29 and 39 are engaged in the threaded notches provided in the pawl block head 19 and in the end of the forming slide block or arm 30, 25 permitting the pawl block to be engaged in any desired position with respect to the ratchet, depending upon the degree of bend to be produced in the pipe or tube, and the long handles are operated, causing the handle 39 to move toward the handle 29, thereby causing the forming slide to move over the pipe and gradually and smoothly bend the same through the desired degree angle for which the pawl block has been set on the ratchet. 35 A quick bending operation of a pipe or tube is thus accomplished in one sweep with the use of the long handles.

By providing the machine with the removable forming slide and the king-pin arrangement, the machine may be readily engaged 40 at any point on a pipe or tube, one end of which is already fixed or secured in position, and a bending operation performed without disturbing the fixed end of the pipe or tube.

45 By engaging the rib or flange 40 in a clamping vise or support 41, as illustrated in Figure 3, the machine may be used as a stationary machine for the purpose of bending pipes, tubes or other articles.

50 It will, of course, be understood that various details of construction may be varied through a wide range without departing from the principles of this invention, and it is, therefore, not purposed to limit the patent granted hereon otherwise than necessitated by the scope of the appended claims.

I claim as my invention:

1. An article bending machine comprising a grooved forming block, spring-controlled holding clips pivotally mounted on the forming block for engaging and holding an article to be bent, a pair of members pivotally mounted on the forming block with one of said members formed to engage an article to be bent, and means connected with said mem-

bers for holding one of said members against relative movement with respect to the forming block when the member engaging the article is advanced around the forming block to smooth out and bend the article. 70

2. An article bending machine comprising a grooved former, means mounted thereon for removably engaging an article to hold the same seated in the grooved former, a member pivotally mounted on the grooved former and including means for holding said member against relative movement with respect to the former during a bending operation, a second member pivotally mounted on the former for engaging the article to be bent, and actuating means connected with said members and operable to cause the member engaged with the article to be advanced toward the other member to bend the article around the grooved former. 80

3. An article bending machine comprising a forming block, means mounted thereon for engaging and holding an article to be bent, a pair of separate members pivotally mounted on the forming block with the article to be bent projecting therebetween, and means for moving said members toward one another to cause one of said members to engage the article and bend the same around the forming block. 90

4. An article bending machine comprising a forming block, spring-controlled clips pivotally mounted thereon for engaging and holding an article to be bent, a ratchet formed on said forming block, a pawl mechanism pivotally mounted on the forming block for coaction with said ratchet, a forming slide pivotally mounted on the forming block for engaging an article to be bent, actuating members removably connected with the pawl mechanism and with said forming slide to cause the forming slide to advance over the forming block to bend an article therearound. 100

5. An article bending machine comprising a forming block, a pawl block and a forming slide, a king-pin pivotally connecting said blocks and slide, spring-controlled clips pivotally mounted on the forming block for removably engaging an article to hold the same in contact with the forming block, a ratchet formed on the side of the forming block, a spring-controlled pawl pivotally mounted on the pawl block for coaction with said ratchet, and members removably connected with the pawl block and with said forming slide to cause the forming slide to move toward the pawl block and bend the article around the forming block, with said pawl and ratchet acting to hold the pawl block against relative movement with respect to the forming block during a bending operation. 110

6. In an article bending machine of the class described, the combination with a forming block, means for engaging an article thereon, a pair of members pivotally mount-

ed on the forming block with the article projecting therebetween, and means connected with said members for intermittently advancing the same around the forming block independently of one another to cause one of said members to advance toward the other during a bending operation of the article and causing the second member to advance away from the first into a new position with respect to the forming block prior to the next bending operation of the article.

7. An article bending machine comprising a forming block including means for holding an article engaged thereon, a member pivotally mounted on said block, a forming slide for engaging the article to be bent, a king-pin for removably holding the forming slide pivotally mounted on the forming block, means for actuating said member and the forming slide to cause the forming slide to advance toward said member to bend the article around the forming block, and acting to hold said slide against relative movement with respect to the forming block after a bending operation and move said member to a new position.

8. An article bending machine comprising a ratchet forming block including spring-controlled means for removably engaging an article and holding the same on the ratchet forming block, a pawl member pivotally mounted on the ratchet forming block and coacting therewith, a bending member pivotally mounted on the ratchet forming block for engaging the article to be bent, and means connected with the pawl member and with the bending member for advancing the bending member toward the pawl member to bend the article around the ratchet forming block and further adapted for moving the pawl member away from the bending member around the ratchet forming block into position for a further bending operation of the article by the bending member.

9. An article bending machine comprising a forming member, means for holding an article to be bent a ratchet on said member, a pawl member pivotally mounted on the forming member for coaction with said ratchet, a bending member, a pin for removably supporting the bending member pivotally upon the forming member, and connected lever means removably connected to the pawl member and to the bending member for advancing the same in successive steps around the forming member.

10. An article bending machine comprising a grooved sheave, a plurality of holding clips pivotally mounted on said sheave for removably engaging an article and holding the same associated with the grooved sheave, a spring carried by said sheave for frictionally retaining the holding clips associated with one another, a member pivotally mounted on said sheave, a spring-controlled pawl carried

by said member, a ratchet formed on said sheave for coaction with said pawl, a bending device adapted to be seated on the article to be bent, a king-pin removably projecting therethrough and through the sheave for pivotally supporting the bending device on said sheave, and means connected with said member and with the bending device for intermittently advancing said member and the bending device around the sheave independently of one another to cause repeated bending operations to be performed on the article by the bending member as it is advanced around the sheave by step by step engagement of said pawl with said ratchet.

11. In an article bending machine of the class described, the combination with a forming block, of a plurality of article engaging and holding members pivotally mounted on said forming block, said members having inter-engageable parts for interlock, and a spring for frictionally holding said holding members in interlocked frictional engagement with respect to one another around the article to be acted upon.

12. A tube bending apparatus including in combination, an arcuate forming member having a tube receiving groove therein, means for holding a tube on said forming member, a swingable member having an elongated tube engaging surface pivotally supported on the axis of said forming member, the tube engaging surface of said swingable member being in its longitudinal direction substantially tangential to the groove of said forming member, and pawl and ratchet means for relatively moving said members for tube bending.

13. A tube bending apparatus including in combination, an arcuate forming member having a tube groove, a king pin in said member, means swingable about the king pin for bending a tube against said forming member, pawl carrying means pivoted to said king pin, and handle means connected to said swingable and said pawl carrying means for moving said means for intermittent bending.

14. A tube bending apparatus including in combination, an arcuate forming member having a tube groove, means swingable about the axis of said forming member for bending a tube thereagainst, pawl carrying means pivoted about the axis of said member, and handle means connected to said swingable and said pawl carrying means for moving said means for intermittent bending, the movement of said means away from each other serving to enable said pawl carrying means to secure a new bite and movement of said members towards each other serving as a bending grip.

15. An article bending machine comprising a former, means thereon for engaging and holding an article to be bent, a pawl

block pivotally mounted on the former, a ratchet on said former, a pawl carried by said pawl block for coaction with the ratchet, a forming slide pivotally mounted on the former for engaging an article to be bent, and operating means connected to said pawl block and said forming slide, said pawl and ratchet and said operating means cooperating when actuated to hold the pawl block against movement with respect to the former to cause the forming slide to move over the article and toward the pawl block to bend the article around the former.

In testimony whereof I have hereunto subscribed my name at Erie, Erie County, Pennsylvania.
